UNITED STATES PATENT OFFICE.

WILLIAM G. HETTICH, OF CHICAGO, ILLINOIS, ASSIGNOR TO STANDARD X-RAY COMPANY, OF CHICAGO, ILLINOIS, A CORPORATION OF ILLINOIS.

TRANSFORMER.

Application filed January 22, 1920. Serial No. 353,321.

To all whom it may concern:

Be it known that I, WILLIAM G. HETTICH, a citizen of the United States, residing at Chicago, in the county of Cook and State 5 of Illinois, have invented certain new and useful Improvements in Transformers, of which the following is a specification.

This invention relates to transformers.

It will be explained as applied to a step- 10 up transformer especially adapted for use with X-ray tubes.

X-ray tubes are operated by high voltage current from a step-up transformer. The high voltage alternating current from 15 the transformer is sometimes rectified before application to the X-ray tube and sometimes it is not.

An X-ray tube ordinarily is required to 20 perform two widely differing classes of service. One class of service necessitates relatively heavy current delivery to the tube for relatively short periods of time; the other class of service ordinarily requires only 25 relatively small current delivery to the tube for relatively long periods of time.

For the heavy current short time service, such for example as some classes of roentgenography, the danger to attendant and patient, from the high voltage heavy current circuits, is relatively small because of 30 the extremely short time of application. The opportunities for inadvertent approach to or contact with the high voltage circuits are greatly lessened as the time of application shortens.

For the relatively small current prolonged time service, such for example as some classes of treatments and direct examinations, the danger to the attendant and patient is relatively great if heavy current will 40 be delivered by the transformer in the event that the resistance of its secondary circuit is materially reduced. The opportunities for inadvertent approach to or contact with the high voltage circuits, resulting in reduction of secondary circuit resistance, are 45 greatly increased as the time of application is lengthened. Heretofore more or less protection during small current prolonged time 50 service has been provided by "ballast" resistance and circuit breakers in the primary circuits of the transformers. However both of these expedients are unsatisfactory, inefficient and unreliable. Ballast resistance has 55 been found inefficient because of the energy

used up or wasted in the rheostat. Ballast resistance has further been found unsatisfactory because the resistance changes as the temperature changes. Circuit breakers have been found unreliable because they do 60 not always operate, and because of the time interval required for them to act.

One of the objects of this invention is to provide greater protection in the operation of X-ray tubes.

Another object is to provide a transformer which may be used for both heavy current and small current service, and will afford adequate protection during the small current service.

Another object is to provide a transformer from which heavy secondary current may be taken when necessary and in which the secondary current is automatically limited to relatively small values when small currents 75 only are required.

Another object is to provide a transformer from which a relatively small secondary current may be taken at a voltage which remains practically constant regardless of the 80 length of time the transformer is used.

Another object is to provide a transformer which provides protection at a lower cost than the cost of a machine made with an ordinary transformer and with a protective 85 rheostat or circuit breaker.

Another object is to provide a transformer which is simple and reliable and obviates the necessity for extraneous protective apparatus.

Other objects and advantages will herein- 90 after appear.

An embodiment of the invention is illustrated in the accompanying drawing which shows one form of transformer in section 95 and diagrammatic circuit connections.

In accordance with this invention the transformer has a single high voltage secondary winding and two low voltage primary windings wound on a common magnetic core.

One primary winding, for convenience called the heavy duty primary, is so related to the secondary and the common core that the leakage of the flux induced by the current in the heavy duty primary varies but little over a wide range of secondary current. In other words the regulation with the heavy duty primary is relatively close or good over a wide range of secondary current. The 110

other primary winding, for convenience called the light duty primary, is so related to the secondary and the common core that the leakage of the flux induced by the current in the light duty primary increases greatly as the secondary current rises above relatively a small amount. In other words the regulation with the light duty primary is relatively poor except for a narrow range 10 of small secondary current.

Thus, when the heavy duty primary is used the secondary current may be greatly increased. On the other hand when the light duty primary is used the value to which the 15 secondary current may rise may be limited to a very small amount.

These characteristics may be obtained by using a rectangular closed iron core on which the secondary winding encircles the heavy 20 duty primary winding which is wound, for example on two opposite legs of the core. The heavy duty primary is preferably relatively long and is distributed evenly over that portion of the core which is encircled 25 by the secondary so that its leakage path is of relatively high reluctance. The light duty primary, on the other hand, should be concentrated and relatively short or otherwise designed to have a leakage path of 30 relatively low reluctance, and placed on one of the other sides of the core, preferably as far removed as possible from the secondary.

The counter magneto-motive force or flux induced by current in the secondary opposes 35 the magneto-motive force or flux induced by current in the primaries. When the heavy duty primary is used the counter magneto-motive force induced by the current in the secondary causes but little of the flux induced 40 by the primary to leave the core and become leakage flux. This condition obtains over a wide range of secondary current values because the relatively high reluctance leakage path keeps the greater part of the flux in the core where it is effective to induce voltage in the secondary. Therefore, with the heavy 45 duty primary the magnetic linkage or coupling between the primary and secondary remains relatively close and the ratio of 50 transformation remains substantially constant over a wide range of secondary current values. As the secondary circuit resistance decreases, with the resultant tendency of the secondary current to increase, the primary 55 current will correspondingly increase to induce such greater secondary current. Thus the regulation with the heavy duty primary is relatively good throughout a comparatively wide range of secondary circuit resistance.

60 When the light duty primary is used, and the secondary current is relatively small, i. e., the secondary circuit resistance is relatively high, the counter magneto-motive force induced by the secondary causes but little of 65 the flux induced by the primary to leave

the core and become leakage flux. For such secondary current values the windings are closely magnetically linked or coupled, and the ratio of transformation may be substantially the same as with the heavy duty 70 primary. However, as the secondary current rises the counter magneto-motive force caused thereby becomes stronger and, because of the relatively low reluctance leakage path, more and more of the primary flux 75 is driven from the core and becomes leakage flux and the windings become relatively loosely magnetically linked or coupled. The leakage flux is ineffective to induce voltage in the secondary, and the secondary current 80 will not rise proportionally to the decrease in resistance of the secondary circuit. Furthermore the characteristic high self induction of a concentrated winding contributes to limit the maximum value to which 85 the light duty primary current may rise. Therefore instead of the secondary current continuing to increase as the resistance of the secondary circuit decreases, which is the condition obtaining when the heavy duty 90 primary is used, the light duty primary may provide an increase in secondary current over a relatively small decrease in secondary resistance, after which the secondary current can increase relatively little upon 95 further lowering of the secondary circuit resistance. Thus the regulation with the light duty primary may be good over a relatively narrow range of secondary current, but becomes relatively poor as this narrow range 100 is exceeded.

The transformer illustrated in the drawing has a closed rectangular iron core 1. A heavy duty primary winding, comprising two coils 2 and 3, connected together in 105 series by a conductor 4, is wound upon opposite limbs 5 and 6, respectively, of core 1. Coils 2 and 3 are relatively long so that the leakage paths of each, that is the paths outside of the core, are of relatively high 110 reluctance.

The secondary winding comprises two coils 7 and 8, wound over the heavy duty primary coils 2 and 3, respectively. The secondary coils may be made up of series of 115 sections separated by insulation 9 in the usual manner and may be connected in series with each other by a conductor 10. The terminals of the secondary winding are respectively connected by conductors 11 and 120 12 to the X-ray apparatus in the usual manner.

The secondary winding is thus superposed upon the heavy duty primary and magnetically closely linked or coupled thereto. This 125 arrangement of the heavy duty primary and secondary windings together with the relatively high reluctance leakage paths of the heavy duty primary provide a substantially constant ratio of transformation between the 130

primary and secondary over a wide range of secondary circuit resistance variation. This condition is due to the fact that the effective magnetic flux; i. e.: the flux influencing the secondary to induce voltage therein, remains about equal to the flux produced by the heavy duty primary. In other words there is relatively little leakage of flux over a relatively wide range of secondary circuit resistance 10 or current.

A light duty primary winding 13 is placed upon one or more of the other limbs of the core. This primary winding is relatively short and loosely linked magnetically 15 with the secondary. Its leakage path is relatively of low reluctance compared to the reluctance of the leakage path of the heavy duty primary. Consequently when the light duty primary is used, the counter magneto-motive force produced by current in the secondary and acting against the flux produced by current in the primary is able, at relatively low secondary current values, to drive part of the total flux of the primary out of 20 that part of the core which underlies the secondary, and thus increase the leakage. This leakage flux is relatively ineffective on the secondary so that, as the leakage increases, the ratio of transformation between the light 25 duty primary and the secondary falls. The leakage flux does not link with the secondary windings and is therefore ineffective to induce voltage therein, thus causing the secondary voltage to decrease and preventing 30 the secondary current from increasing proportionately to the decrease in resistance of the secondary circuit. The most of this leakage flux leaves the core near one end of the light duty primary winding and enters the 35 core near the other end of that winding in much the same manner that flux travels through the air around the winding of a choke coil consisting of a straight iron core with a winding encircling the middle portion 40 thereof. This choke coil action of the light duty primary contributes to limit the value to which the primary current and the magneto-motive force induced thereby may rise when the resistance of the secondary circuit 45 is greatly reduced. The output of the secondary winding is thus limited by two factors, when the light duty primary winding is used: First, the secondary voltage decreases as the secondary current and the 50 leakage flux increase, and secondly, the choke coil action of the small capacity primary assists in limiting the magneto-motive force available to produce the flux which induces voltage in the secondary. Until the 55 counter magneto-motive force is able to drive out lines of force created by the light duty primary against the relatively low reluctance of the leakage path, the leakage will be relatively small, the magnetic coupling 60 will be relatively close and the ratio of

transformation will remain relatively constant. When, however, the counter-magneto-motive force of the secondary is able to appreciably increase the primary flux flowing over the relatively low reluctance leakage 70 paths the magnetic coupling becomes relatively loose and the ratio of transformation falls. Consequently as the secondary circuit resistance decreases, the current increase proportionally over a small range; 75 but, when the secondary resistance drop exceeds a relatively small amount, the current no longer increases proportionately to the resistance drop. The amount of current which may be taken from the secondary 80 without any excessive drop in secondary voltage is governed by the reluctance of the leakage path of the light duty primary windings.

The terminals of the heavy duty and light duty primary windings may be connected to a source of alternating current 14, through suitable regulating devices, in the usual manner. One terminal of each winding is connected by conductors 15, 16 and 17 85 to one terminal of the source. The other terminal of the heavy duty primary is connected to a switch contact 18 by a conductor 19. Similarly the other terminal of the light duty primary is connected to a switch contact 20 by a conductor 21. Contacts 18 and 20 may be alternately connected to the other terminal of source 13 by a switch blade 22.

When switch blade 22 is moved to engage contact 18 the transformer is connected for 100 heavy current short time service. The resistance of the secondary circuit may be reduced over a wide range to provide the necessary current for heavy duty service.

When switch blade 22 is moved to engage 105 contact 20, the transformer is connected for small current long time service. Over a relatively small range of secondary circuit resistance drop the secondary current will proportionally increase. However, when 110 this relatively small range of resistance drop and resultant current increase is exceeded, for example when a patient or attendant should touch or dangerously approach the high voltage circuits, the counter magneto-motive force induced by the current in the secondary causes the leakage of magneto flux to increase rapidly and the current rise in the secondary will be relatively small. The secondary voltage will fall rapidly almost to zero if the secondary current much exceeds the low value which the transformer 115 is designed to deliver.

Thus with one transformer the common 125 secondary may be caused to possess two radically different characteristics of output. One in which the secondary current may be increased over a wide range and the other in which the secondary current can not be increased beyond a relatively small amount. 130

Having described my invention what I claim as new and desire to secure by Letters Patent, is:—

1. A transformer having a secondary winding, and a pair of primary windings associated therewith, one primary being associated with the secondary so that the ratio between effective and leakage fluxes remains substantially constant over a wide variation 5 in secondary circuit resistance and the other primary being associated with the secondary so that the ratio between effective and leakage fluxes varies materially over a relatively narrow range of secondary circuit resistance.
2. A transformer having a core with an effective magnetic circuit of low reluctance, a secondary winding thereon, a heavy duty primary winding on the core and having a relatively high reluctance leakage circuit, and a light duty primary winding on the core and having a leakage circuit of relatively low reluctance.
3. A transformer having a substantially closed core of magnetic material, a secondary winding wound over a portion of the core, a heavy duty primary wound over the same portion of the core as the secondary so that the flux induced in the core by the primary is largely effective on the secondary over a wide range of secondary resistance, and a light duty primary wound on a different portion of the core so that, below a relatively narrow range of secondary resistance, the flux induced by the primary is

largely a leakage flux and ineffective on the secondary.

4. A step-up transformer having a substantially closed core of magnetic material, a common secondary winding wound over a portion of the core, a heavy duty primary winding wound upon the core in superposed relation to the secondary and having relatively high reluctance leakage paths so that over a wide range of secondary circuit resistance the leakage is relatively constant, and a light duty primary winding wound on a different part of the core and having relatively low reluctance leakage paths so that below a relatively narrow range of secondary circuit resistance the leakage becomes relatively great to limit the current and voltage output of the secondary.

5. A transformer having a closed magnetic core, a secondary winding on the core, a heavy duty primary winding on the core and relatively closely magnetically linked to the secondary winding under all normal ranges of secondary circuit resistance, and a light duty primary winding which is relatively closely magnetically coupled to the secondary winding until the secondary circuit resistance decreases through a relatively narrow range and becomes relatively loosely magnetically coupled to the secondary winding when the secondary circuit resistance decreases below the range.

In testimony whereof I hereunto subscribe my name.

WILLIAM G. HETTICH.
